UNITED STATES PATENT OFFICE.

JAMES A. BYERS, OF CENTERVILLE, TENNESSEE.

TREADLE MECHANISM.

1,036,559.

Specification of Letters Patent. Patented Aug. 27, 1912.

Application filed September 14, 1911. Serial No. 649,310.

To all whom it may concern:

Be it known that I, JAMES A. BYERS, a citizen of the United States, and resident of Centerville, in the county of Hickman 5 and State of Tennessee, have invented certain new and useful Improvements in Treadle Mechanism; and I do hereby declare the following to be a full, clear, and exact description of the same, reference being had to the accompanying drawings, forming part of this specification, and to the figures and letters of reference marked thereon.

This invention relates to treadle power 15 mechanism and is particularly designed for use in connection with sewing machines, although applicable to light power machines of any character, such as are adapted to be driven by the operator's feet, and especially 20 where driven with the operator seated.

The objects of the invention are to provide a simple arrangement with which the power will be economized, dead centers, to 25 a large extent, eliminated, and the strains practically all transmitted from the treadle to the crank shaft as tension strains in the connecting rods in contradistinction to compression or thrust strains.

Referring to the accompanying drawings, 30 Figure 1 is a view looking at the front of a sewing machine table and a treadle mechanism embodying the present improvement; Fig. 2 is a detail side elevation showing the treadle mechanism and crank shaft separate 35 from the table frame.

Like letters of reference in the several figures indicate the same parts.

In said drawings, the letter A indicates 40 a sewing machine table of ordinary construction, having legs B, and C indicates the usual belt and fly wheel, which, in the present instance however, is preferably mounted on a crank shaft D journaled in bearings 45 E depending from the machine table, in order that the crank shaft may have a crank at each end. The cranks on the shaft, indicated by the letter G, are set in opposite relation to each other. In the lower portion 50 of the machine frame there is pivotally mounted a treadle composed of two sections H and H', the section H projecting forwardly of the axis, and the section H' rearwardly thereof. These two sections are free 55 to swing upwardly independently of each other, but are preferably provided with

downwardly extending projections h which will limit or prevent their independent downwardly swinging movements. In other words, the projections will prevent the two treadle sections from assuming an angular position with relation to each other, below the medial line, but will permit them to assume an angular position with relation to each other above said line. The outer ends or portions of the treadle sections are connected with the cranks of the crank shaft, the section H being connected by a connecting rod I with one crank, and the section H' by a connecting rod I' with the other crank. The two connecting rods, it will be noted 70 from Fig. 2, diverge from the crank shaft to the treadle sections, and, owing to the separation of their lower ends, the dead centers of each crank with relation to its connecting rod and treadle section is displaced angularly around the crank shaft with relation to the dead center of the other crank. Owing to this condition it is practically impossible for the shaft to stop on a dead center or in a position in which it cannot be 80 started by pressure downwardly upon one or the other of the treadle sections.

In operation, during each complete revolution of the crank shaft, the treadle sections move angularly with relation to each other, and hence they may be mounted upon a fixed axis, such, for instance, as the usual cross rod found at the bottom of sewing machine table frames. With a treadle mechanism of this character, the driving 85 effort of the operator is practically all a downward pressure, first on one section of the treadle and then on the other; there are no thrust strains imposed upon the connecting rods; and the treadle sections are 90 each supported at the front and rear edges so that there is little danger of said parts being broken.

Having thus described my invention, what I claim as new and desire to secure by Letters Patent of the United States, is;

1. In a treadle mechanism such as described, the combination with a crank shaft having oppositely disposed cranks thereon, of separate treadle sections pivotally supported at their proximate edges and projecting in opposite directions from their axis, and connecting rods connected directly to the outer ends of the treadle sections and respective cranks whereby said treadle sec- 105 110

tions may assume different angular positions with relation to each other during the rotation of the crank shaft.

2. In a treadle mechanism such as described, the combination with a crank shaft having oppositely disposed cranks thereon, of separate treadle sections pivotally mounted on a common axis at their proximate edges and projecting in opposite directions therefrom, connecting rods connected directly to the free outer ends of said treadle sections and cranks respectively, so that said treadle sections are free to assume different angular positions with relation to each other during the rotation of the crank shaft.
3. In a treadle mechanism such as described, the combination with the crank shafts having oppositely disposed cranks

thereon, of the separate treadle sections pivotally mounted on a common axis at their proximate edges and projecting in opposite directions therefrom and having downwardly extending projections for limiting their relative angular position in a downward direction, and connecting rods connected directly to the free outer ends of said treadle sections and respective cranks, the arrangement being such that the treadle sections may assume different angular positions with relation to each other during the rotation of the crank shaft.

JAMES A. BYERS.
